FLUID DRAINAGE MEANS FOR WASHING
AND RINSING MACHINESCharles Hirsch, South Bend, Ind., assignor to
American Wheelabrator & Equipment Corpora-
tion, a corporation of Delaware

Application July 29, 1944, Serial No. 547,167

2 Claims. (CL 134—96)

1

The invention relates to cleaning machines of the type used in the industry for the cleaning of metal.

Among its principal objects, the invention provides a combination washing and rinsing machine in which the washing and rinsing operations are successively performed in the same cleaning chamber. The invention provides mechanism permitting an immediate change-over from the washing to the rinsing operation.

Among its further objects and features, the invention provides a washing and rinsing machine so constructed that a dilution of the washing liquid by the rinsing liquid at the time of change-over from the washing to the rinsing operation is prevented.

The invention further provides safety mechanism for protecting the operator of the machine from washing and rinsing liquid if accidentally the cleaning chamber of the machine is opened while the machine is in operation. The safety devices further prevent the washing and rinsing mechanism from being brought into operation while the cleaning chamber is open.

The invention further provides numerous features of design resulting in a compact and efficient washing and rinsing machine particularly suited for the cleaning of large quantities of small parts such as metal castings, machined parts and the like.

These and further features, advantages, and details of the invention will appear more fully from the detailed description which follows accompanied by drawings, showing, for purely illustrative purposes, machines and structure embodying the present invention.

Although the novel features which are believed to be characteristic of the invention will be particularly pointed out in the claims appended hereto, the invention itself, its objects and advantages, and the manner in which it may be carried out may be better understood by referring to the following description taken in connection with the accompanying drawings forming a part hereof, in which

Fig. 1 is a side elevational view, partly in section, of a combination washing and rinsing machine;

Fig. 2 is an elevational front view, partly in section, of the machine shown in Fig. 1.

In the drawings accompanying and forming part of this description the invention is explained by reference to specific structure and it will be understood that the details may be modified in various respects without departure from the broad aspects of the invention.

2

Similar reference characters refer to similar parts throughout the drawings and the specification.

The machine shown in Figs. 1 and 2 consists generally of cleaning unit A and a tank unit B. The units may be made integral or separate and interchangeable in order to permit the use of various types of cleaning unit with the same form of tank unit, as desired. The cleaning unit 5 A comprises a front wall 11, side walls 12 and 13, a top wall 14, and a hopper-shaped bottom 15. The walls enclose a cleaning chamber 16 which is accessible from the outside through a vertically slideable door 17 in the front wall 11. The interior of the cleaning chamber 16 contains suitable mechanism for supporting the parts to be cleaned, in the illustrated embodiment an endless tumbling belt or conveyor 18' trained around rollers 18, 19 and 20 and guided by an appropriate guide member 21 to form a trough 22 in which the parts to be cleaned may be placed. The tumbling belt is normally driven in the direction of the arrow 23, power being applied to the driven shaft 24 of the roller 18 through a chain 25, reduction gear 26, and a belt 27 from a motor 28.

Washing or rinsing liquid is directed into the space of the trough 22 from a series of nozzles 29 arranged in spray heads 30 and 31. Spray head 30 is supplied with liquid from a main supply valve 32 through a conduit 33. The spray head 31 is supplied with liquid through a conduit 34 in which a valve 35 is arranged permitting adjustment of the strength of the jets issued from the lower spray head 31.

The tumbling belt 18' is composed of links or mesh permitting the jets issued from the lower spray head 31 to pass through the belt and reach the parts placed in the trough 22. Liquid issued 40 from the upper spray head 30 drains through the mesh or links of the belt and collects in the hopper shaped bottom 15 provided with a drain port 36.

The tank unit B comprises a front wall 37, side walls 38 and 39, a back wall 40 and a bottom 41 forming a tank resting on a base 42.

The bottom wall 41 of the tank slopes towards a flush port 43 through which the tank may be flushed. A conduit 44 extends from the port 43 and leads to the sewer or other point of liquid disposal. The conduit 44 is normally closed by a flush valve 45.

A suction port 46 is arranged in the side wall 39 of the tank. Its entrance is guarded by a screened container or basket 47 to prevent impurities from entering the suction port. The con-

tainer 41 extends with its upper edge 48 above the normal liquid level indicated at 49.

From the suction port 46 a conduit 58 leads to the intake 51 of a pump 52 driven by a motor 53. The pump has a discharge 54 to which is connected a supply conduit 55 for washing liquid. The supply conduit leads to a three-way valve 56 having a movable valve member 57.

A supply conduit 58 for rinsing liquid also leads to the three-way valve 56 which, depending on the position of the movable valve member 57, admits either washing liquid from the supply conduit 55 or rinsing liquid from the supply conduit 58 to the main supply valve 32.

Liquid flowing from the drain port 36 strikes a movable channel-shaped shed plate 59 mounted on a tilt shaft 60. The tilt shaft 60 is mounted in bearings 61 and 62 in the side walls 38 and 39 of the tank unit, respectively. The shaft permits tilting of the shed plate into two different positions in order to direct the liquid into the space in the tank containing washing liquid or into a compartment for rinsing liquid.

In the position shown in Fig. 1, the liquid is directed by the shed plate 59 into a strainer basket 63 having walls of wire mesh. The strainer basket 63 rests on tracks of angle iron, one track being visible in Fig. 1 at 64. The tracks are secured to the tank structure and permit removal of the strainer basket 63 from the tank for cleaning. The strainer basket runs on the track 64 on rollers 65 and may be removed from the interior of the tank through a door 19 in the tank unit B. A second strainer basket 66 is releasably connected to the first basket 63 by a hook 67 and may be moved into the place of basket 63 to strain the washing liquid while basket 63 is removed from the machine for cleaning. After the cleaning basket 63 is put back on the tracks, it is hooked to basket 66 and both baskets are moved into the position shown in Fig. 1.

The level of the washing liquid in the tank is determined by an upper edge 68 of a compartment or trough 69 extending along the front wall 37 and the side wall 38 and sloping towards a discharge port 70. The discharge port 70 is connected to the discharge conduit 44 by a duct 71 permitting excess of washing liquid to be drained off and the proper liquid level to be maintained in the tank. The shed plate 59 may be moved into the position shown in dotted lines in Fig. 1 by tilting of the shaft 60. In the tilted position liquid is discharged into the trough 69 whence it is drained off to a point of liquid disposal in the manner hereinbefore described.

The tilting of the shed plate 59 with its tilt shaft 60 is done manually by operating a lever 72 actuating the tilt shaft 60 through an appropriate mechanism. The mechanism comprises an operating shaft 73 secured to the valve member 56. A lever 75 is connected to the operating shaft 73 and has connected thereto one end of a connecting rod 76. The other end of the connecting rod 76 is forked as at 77. A pin 78 extends through the forked end 77 and is movable in a curved slot 79 of a cam member or sector 80 secured to the tilt shaft 60.

A releasable detent is provided in the cam member or sector 80 and comprises a catch pin 81 acted upon by a helical spring 82. The spring is held in the cam member by a set screw 83 and permits the catch pin 81 to be forced out of the path of the pin 78 if a sufficient force is exerted to compress the spring 82. The purpose of the releasable detent mechanism will become more apparent from the description of the operation 75 open position the pin 81 travels in the elongated

of the machine which follows further below. The operating mechanism connecting the tilt shaft 60 with the operating shaft 73 and the handle 72 provides an operative interconnection of the shed plate 59 and the three-way valve 56 such that liquid flowing from the cleaning chamber is directed into the tank for filtering and reuse while the three-way valve 56 is in a position admitting washing liquid to the spray heads, and that the liquid is directed into the trough 69 and drained when the three-way valve is in a position to admit rinsing liquid to the spray head.

The main supply valve 32 has an operating shaft 84 connected to it. A hand lever 85 is secured to the operating shaft 84 by a nut 86. The operating shaft 84 is supported in a bracket 87 secured to the front wall 11 of the cleaning unit.

The hand lever is double-armed and has an elongated slot 88 therein engaging a pin 89 and a push bar 90. The push bar 90 is slidably supported in the bracket 87 at 91 and 92 and cooperates with a tiltable latch member 93. The latch member 93 is pivotally mounted at 94 in such manner that its own weight causes it to tilt into the position shown in dotted lines in Fig. 2 if the member is free to do so after retraction of the push bar 90. The latch member has an end surface 95 adapted to abut and block the end of the push bar 90 if the latch member is in the position indicated in dotted lines. The other end of the latch member has projections 96 and 97 defining a space therebetween into which the end of a locking member 98 fits. The locking member 98 is secured to the sliding door 17 by bolts 99.

In the position shown in solid lines in Fig. 2 the door 17 is firmly locked in its closed position by the locking mechanism, the locking member 98 being held between the projections 96 and 97 of the latch member 93 which, in turn, is prevented from turning by the push bar 90. In this position the main supply valve operated by the lever 85 is open and washing and rinsing liquid is being discharged into the cleaning chamber.

The door 17 can only be opened after shutting off the supply of liquid by moving the lever 85 of the supply valve into the position shown in dotted lines. In this position the push bar is retracted sufficiently to recede from underneath the tiltable latch member which will then move into the position shown in dotted lines if the door 17 is open. The latch member tilts when the door is opened and remains in the tilted position owing to its own unbalance. In the tilted position it blocks the push bar 90 and prevents an opening of the main supply valve 32 as long as the door is open. When the door is moved toward its closed position the locking member 98 strikes the projection 97 of the tiltable latch member unblocking the push bar 90 and permitting free movement of the valve lever 85 into the position in which the valve is open. As the valve lever 85 is moved towards its open position the push bar 90 moves underneath the end of the tiltable latch member 93 locking the door in its closed position.

The door 17 is provided with a bracket 100 near its upper edge having a pin 101 therein movable in an elongated slot 102 in one end of a rod 103. The other end of the rod is pivotally connected at 104 to a chute 105. The chute 105 is hingedly secured at 106 to the front 11 of the cleaning unit.

The door 17 may be moved in a vertical direction by a handle 107 secured to the door. As the door is being moved upwardly towards its open position the pin 101 travels in the elongated

slot 102 of the rod 103 until it reaches the upper end of the slot. The rod then moves with the door causing the chute to tilt and assume the position shown in dotted lines for the discharge of contents from the cleaning chamber 16.

The operation of the machine is as follows:

Parts to be cleaned are placed in the trough 22 through the open door 17. The door is then closed causing the locking member 98 near the lower right hand corner of the door to engage the rotatable latch member 93, moving the member into a position in which it will unblock the push bar 90 of the hand lever 85 which operates the main supply valve.

The lever 72 operating the three-way valve 56 is then moved into a position in which the supply conduit 55 for washing liquid is connected to the main supply valve 32 and in which the shed plate 59 is so tilted as to discharge liquid into the strainer basket 63. The tumbling belt 16' is then started in the direction of the arrow 23 causing the parts in the trough 22 to be carried upwardly to a point where they will tumble down into the trough under the influence of gravity thus causing all surfaces of the parts to become exposed to the action of the washing and rinsing liquids.

Washing liquid is admitted to the spray heads by opening the main supply valve 32 by swinging the hand lever 85 into the position in which it is shown in Fig. 2. The spray heads 29 and 31 now discharge strong jets of washing liquid against the tumbling parts both from above and from below. The lower spray head 31 serves a triple purpose: It sprays the parts in the trough 22 through the mesh of the belt 16', it cleans the belt proper as it passes over the spray head, and thirdly it loosens up the parts in the trough. The jets of liquid may be adjusted in strength at the valve 35 to obtain a jet pressure not quite enough to blow the parts out of the trough, but sufficient to prevent the parts from packing too tightly in the trough, thereby facilitating the removal of impurities.

At the end of the washing period the lever 72 operating the three-way valve 56 is turned to admit rinsing liquid to the spray head. The actuation of the lever 72, in addition to operating the three-way valve 56, causes the connecting rod 76 to tilt the shed plate 59, the pin 78 being releasably held at this time at the end of the curved slot 79. The movement of the lever 72 into the rinsing position causes the shed plate to tilt simultaneously into the position shown in dotted lines in Fig. 1 so that rinsing liquid about to issue from the spray heads will not flow into the tank containing washing liquid and dilute the washing liquid but will flow into the compartment or trough 69 whence it is drained into the sewer or other point of liquid disposal. Since the stroke of the connecting rod 76 is larger than the movement of the point at which the cam member or sector 80 is engaged by the pin 78 the pin will be forced past the releasable catch pin 81 and travel in the curved slot 79 towards its other end.

If the lever 72 is turned to change from rinsing liquid to washing liquid, the three-way valve is actuated immediately but the shed plate is tilted only with a certain amount of delay caused by the movement of the pin 78 in the curved slot 79 until it reaches the releasable detent 81. This delayed actuation of the shed plate insures complete drainage of all rinsing liquid into the discharge trough 69 before the shed plate 59 moves

into the position in which liquid is directed into the tank for washing liquid.

At the end of the washing and rinsing periods the flow of liquid is stopped by turning off the main supply valve 32. The tumbling of the parts may then be continued for some time to rid the parts from liquid. The drying is aided very effectively by the tumbling of the parts causing the parts to be turned over continuously and drops of liquid to be shaken off. At the end of the drying period the belt 16' is stopped and the door opened which is possible because the main supply valve is in its closed position permitting tilting of the latch member 93. The opening movement of the door causes the discharge chute 105 to move into the position shown in dotted lines in Fig. 1.

The parts may then be discharged from the trough shaped portion 22 of the belt by driving the belt in the opposite direction causing the parts to climb over the roller 20 and slide down the chute 105 into a receptacle.

If an appreciable amount of impurities has collected in the strainer basket 63, the basket may be removed through the door 108 in the tank unit B for cleaning while the strainer basket 63 is removed from the machine, the second basket 66 takes its place, thus making it unnecessary to interrupt the operation of the machine during the cleaning of the basket 63.

Sediment which after some time collects at the bottom of the tank may be removed by opening the flush valve 45 and flushing the tank with liquid. A pressure hose may be used for this purpose or the facilities of the machine itself may be employed as follows: The lever 72 is moved into the rinse position while the shed plate is held in the washing position, or by manually turning the shed plate back into the washing position after the three-way valve is moved into the rinsing position. This is possible by overcoming the force exerted by the releasable detent 81, the curved slot 79 being long enough to permit such movement. Rinsing liquid will then flow into the tank B.

A movement of the valve lever 72 into the washing position while the supply of fluid is interrupted by the closed main supply valve 32 restores the original engagement of the operating segment or cam member 80 of the shed plate and the connecting rod 76.

The delayed operation of the movable shed plate is a feature of considerable value, particularly where the washing and rinsing operations are short and the change-over from one operation to another occurs frequently.

Obviously, it is not necessary that a cleaning unit A employing a tumbling belt be used in connection with a tank unit B shown in Figs 1 and 2. Other forms of mechanism may be employed for exposing the parts to be cleaned to the jets of liquid, and the tank unit B may advantageously be used with any convenient form of cleaning unit. It is, therefore, not necessary that all the features of this invention be used conjointly since they may be used in various combinations with great advantage.

Obviously, the present invention is not limited to the specific embodiments herein shown and described. Various modifications, substitutions, additions, and omissions will readily occur to persons skilled in the art and do not involve any departure from the scope and spirit

What is claimed is:

1. A washing and rinsing machine comprising, in combination, a cleaning chamber having a drain port; spray means for discharging a jet of liquid into said cleaning chamber; means for selectively supplying washing and rinsing liquid to said spray means; a compartment adapted to receive washing liquid; a compartment adapted to receive rinsing liquid; a movable shed plate in the path of liquid flowing through said drain port for directing the liquid in one or the other direction to flow into the compartments for washing and for rinsing liquid, respectively and an actuating mechanism for jointly adjusting said selectively supplying means and said shed plate, said mechanism including a sector connected to said shed plate for tilting said shed plate, said sector having an elongated aperture therein, a pin operatively linked to said valve for movement therewith, said pin engaging said aperture; and a yielding detent for releasably detaining said pin at one end of said elongated aperture.

2. A washing and rinsing machine comprising, in combination, a cleaning chamber having a drain port; spray nozzles in said cleaning chamber; a compartment for washing liquid; a source of rinsing liquid; a valve for selectively connecting said nozzles to said compartment and said source, respectively, to receive liquid therefrom; a tiltable shed plate in the path of liquid flowing through said drain port for directing the

5 liquid in one direction or the other to flow into said compartment in one position, and to a different point of disposal in the other; and a joint actuating mechanism for adjusting said valve and tilting said shed plate, said actuating mechanism including a sector connected to said shed plate for tilting said shed plate, said sector having an elongated aperture therein, a pin operatively linked to said valve for movement therewith, said 10 pin engaging said aperture; and a yielding detent for releasably detaining said pin at one end of said elongated aperture.
